MICROFICHE VIEWER

James B. Single, Hilliard, Ohio, assignor to Nu-Way
Automotive Systems, Inc., Columbus, Ohio, a corpora-
tion of Ohio

Filed Aug. 26, 1969, Ser. No. 18,856

Term of patent 14 years

Int. Cl. D16—03

U.S. Cl. D61—1

Fig. 1

Fig. 2

Fig. 3

FIG. 4

FIG. 5

FIG. 6

FIG. 1 is a perspective view of a microfiche viewer taken generally from the front, right side corner thereof;

FIG. 2 is a plan view thereof;

FIG. 3 is a bottom view thereof;

FIG. 4 is a left side view thereof;

FIG. 5 is a front view thereof; and

FIG. 6 is a rear view thereof.

I claim:

The ornamental design for a microfiche viewer, substantially as shown.
